Primary Examiner — Deanna L Fluegeman(74) *Attorney, Agent, or Firm* — Fenwick & West LLP(57) **CLAIM**

The ornamental design for a smartcard reader, as shown and described.

DESCRIPTION

FIG. 1 is a front perspective view of a smartcard reader.

FIG. 2 is a front view of the smartcard reader.

FIG. 3 is a rear view of the smartcard reader; and,

FIG. 4 is a side view of the smartcard reader.

The evenly-spaced broken lines in the drawings illustrate unclaimed portions of the smartcard reader and form no part of the claimed design.
